UNITED STATES PATENT OFFICE

FRANCIS HEGENBARTH, OF NEW ORLEANS, LOUISIANA

INTERMEDIATE CARRIER FOR SUGAR CANE MILLS

Application filed September 22, 1930. Serial No. 483,669.

The present invention relates to improvements in intermediate carriers for sugar cane mills, and has for an object to provide an improved intermediate carrier used primarily for the breaking up of lumps of bagasse, in addition to advancing the bagasse blanket from one mill to another.

Another object of the invention is to provide an even distribution of the bagasse blanket laterally over the carrier bottom plate.

A further object of the invention is to provide an improved device which will operate upon the bagasse coming from a cane mill in such a manner as to churn and turn over the bagasse particles, exposing all surfaces in a manner which permits of thorough maceration, whereby to secure the best possible penetration of the bagasse with the macerating liquid.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a longitudinal vertical section taken through an apparatus constructed according to the present invention.

Figure 2 is a fragmentary horizontal section taken through the same.

Figure 3 is a view similar to Figure 1 but showing a modified form.

Referring more particularly to the drawings, the first mill and the second mill are so designated by legends on the drawings and these mills are of the usual form.

The first mill is provided with a cane roll 5, a bagasse roll 6 and a top roll 7. The crushed cane is forced into the throat 8, being discharged from the first mill and pushed upwardly over the bottom plate 9. Upon reaching the apex 10, the compact mat of bagasse breaks up and drops onto bottom plate 11 of the carrier mid-section. In this carrier mid-section are a number of rotating helical conveyors 12 and 13. These conveyors act to thoroughly loosen and disintegrate the ba-

gasse lumps which are still intact. Maceration is applied at this point to best advantage, since the bagasse is turned over and all surfaces exposed to the maceration fluid.

The maceration fluid pipe is shown at 14 and is provided with nozzles 15. An additional pipe 16 for steam or liquid may be located in the angle between the ledge or apex 10 of the bottom plate 9 and the forward inclined section 17 of the front wall 18 of the carrier mid-section. The screw conveyors 12 and 13 are provided with stub shafts 19 at their forward ends only. These stub shafts pass through the front walls 18 of the carrier section and are mounted for rotation in bearings 20.

The screw conveyors consequently resemble cork screws in general appearance. The shaft is omitted on the greater part of the screws to avoid entangling long pieces of cane that occasionally pass with the bagasse. The screws may be rotated by chain drive or otherwise. In this instance, bevel gears 21 are provided upon the stub shafts 19 meshing with similar bevel gears 22 on a shaft 21 that is driven by a chain 23 and sprocket connections from the jack shaft 24, which in turn is driven by chain and sprocket connections 25 from the first mill. The rotation of the screw members 12 and 13 will push the bagasse blanket between the rolls of the second mill, thus producing a force feed effect.

Slip joints 26 and 27 make it possible to readily lift out the entire mid-section 28. The side plates of the mid-section are provided with lifting holes or shackles 29. Filler pieces 30 are placed in the bottom part of the mid-section adjacent the lower portions and sides of the screws 12 and 13 to prevent accumulation of bagasse or trash where the rotation of the screw would not remove such matter.

The screws or screw flights 12 and 13 will be placed in the bottom part of the mid-section parallel to one another and in such numbers as the carrier width may require. One flight of screw may be sufficient for a very narrow intercarrier. For a standard intercarrier, say 66 inches wide, four 10 inch diameter screws or flights would probably suf-

fice. These flights or screws could be made relatively short to provide the pushing power for the blanket which will mat readily again after leaving the screw flights.

5 However, the nature and condition of the bagasse, and the distance between first and second mill will determine the length of the screw flights.

10 The construction readily permits the addition of a plate or sheet covering 31 for fully enclosing the carrier, should it be deemed preferable to apply steam to the bagasse blanket. Where a number of the screws or flights 12 and 13 are employed they will preferably be made alternately right and left hand, as shown in Figure 2. This will prevent an uneven distribution of the bagasse blanket laterally over the carrier bottom plate.

20 As shown more particularly in Figure 3, a slightly modified form of arrangement is shown, where an inclined mid-section is employed. The inclined bottom plate 32 has an apex 33 in its central portion. This inclined carrier pushes the bagasse blanket upward toward the apex point 33 from where it is fed by gravity over the bottom plate 34 between the rolls of the second mill.

30 It will be appreciated that with the use of the invention no carrier drag chain, apron chain or slats are employed, which parts are subject to rapid wear and frequent breakage.

35 With the present invention the bagasse mat is thoroughly broken up and maceration applied most effectively with all particles of bagasse exposed to maceration.

40 With the invention, there is an extremely effective force feed into the mill; and there results absolute cleanliness with no trash under carrier and between the mills. For these reasons, the invention eliminates inversion losses and reduces labor.

45 The main section or the mid-section of the carrier is easily removable. All moving parts are in this mid-section and thus may be readily accessible. The entire inter-carrier may be fully enclosed for the steaming of bagasse if desired.

50 Easy access is had to all parts of the inter-carrier and to the mill rolls under carrier during operation.

55 Throughout the specifications, reference is made to mills 1 and 2. Modern mill trains consist of 3 to 6 and 7 mills. When, therefore, referring to mills 1 and 2, in order to avoid any misunderstanding, this phrase refers to any two mills of the train.

60 Certain conditions may require the placing of the screw flights in the mid-section part of the carrier at such close centers as to produce overlapping of the screw flights. In such a case, it will be preferable to use only screw flights of the same hand and a certain synchronization of rotation must be established to

prevent interference with each other of the rotating screw flights.

It is obvious that various changes and modifications may be made in the details of construction and design of the above specifically described embodiment of this invention without departing from the spirit thereof, such changes and modifications being restricted only by the scope of the following claims:

What is claimed is:—

1. In a sugar cane mill, a wide intermediate carrier section between two mills, having a bottom plate, a number of screw flights having stub shafts at one end only mounted across the bottom plate in an intermediate portion of the carrier, and means for rotating said screw flights.

2. In a sugar cane mill, an open intermediate carrier section having a bottom plate with a forward wall adjacent the point of inlet of the material, a number of screw flights mounted along the bottom plate and having stub shafts at one end only extending through the forward wall, and means for rotating said screw flights.

3. In a sugar cane mill, an intermediate carrier having a bottom plate with a forward inclined wall, an entrance throat from one mill having an apex point extending over said forward wall, a number of screw flights extending along said bottom plate with their forward ends adjacent the forward wall, fillers in the corner portions of said bottom and forward walls below the flights, stub shafts on the forward ends of the screw flights only extending through said forward wall, bearings externally of said forward wall for the stub shafts, and means connected with the forward ends of the stub shafts for driving said flights.

4. In a sugar cane mill having a first mill and a second mill, an intermediate carrier section having an open top disposed between the mills, an inclined bottom wall for the intermediate carrier extending from a low point adjacent the first mill to a high point relatively close to the second mill, screw conveyor flights extending parallel to, and in the lowest portion of, said bottom wall whereby to form an open blanket of material, and means substantially above said conveyor flights for spraying maceration liquid upon the open blanket.

FRANCIS HEGENBARTH.
